UNITED STATES PATENT OFFICE.

CHARLES E. BROMAN, OF GRAND RAPIDS, MICHIGAN, ASSIGNOR TO GRAND RAPIDS SHOW CASE COMPANY, OF GRAND RAPIDS, MICHIGAN, A CORPORATION OF MICHIGAN.

LIGHT BRACKET.

Application filed September 17, 1923. Serial No. 663,051.

To all whom it may concern:

Be it known that I, CHARLES E. BROMAN, a citizen of the United States of America, residing at Grand Rapids, in the county of 5 Kent and State of Michigan, have invented certain new and useful Improvements in Light Brackets; and I do hereby declare the following to be a full, clear, and exact description of the invention, such as will enable others skilled in the art to which it 10 appertains to make and use the same.

This invention relates to improvements in light brackets and more particularly to swinging brackets for electric lights and its 15 object is to provide a device of this character which will be extremely simple in construction, easy to manufacture and assemble and attractive in appearance. The device is provided with various novel features of construction and arrangement as hereinafter 20 more fully described and particularly pointed out in the claims, reference being had to the accompanying drawings, in which:

25 Fig. 1 is a perspective view of a light bracket embodying this invention, with one end broken away,

Fig. 2 is a vertical section of the same taken on the line 2—2 of Fig. 3.

30 Fig. 3 is a sectional plan of the same on the line 3—3 of Fig. 2, and

Figs. 4 and 5 are perspective views of parts of the device dis-assembled.

Like numbers refer to like parts in all 35 of the figures.

1 represents a swinging arm made of tubing which is preferably square in cross section, although round or other shaped tubing may be used. The outer end of the arm which 40 is broken away in the drawing supports an electric light, the electric conducting wires 2 for which extend through the tube. At the other end of the tube an inverted cup-like member 4 is attached, one side of the member 45 being split and the parts 5 being turned outward to permit the tube to pass inside of the cup. The tube is fastened to the cup by brazing or welding it thereto and the inner end of the tube extends beyond the center 50 of the cup 4 and is pierced for the passage of the pivot screw 6. The sides of the tube are turned outward at 7 to form a rounded surface which is engaged by the wires 2 so that the insulation on the wire will not be cut or 55 worn. The out turned parts 5 lying adjac-

cent the sides of the tube are welded thereto.

The main body portion 8 of the bracket by which the device is attached to a wall or other object is formed of sheet metal having two vertical flanges 9 which engage the wall, 60 and between the flanges 9 the metal extends outward at right angles forming the side walls 10 which are joined by the front portion 11. The top of the front portion 11 and also the forward top edges of the sides 65 10 are lower than the tops of the flanges 9 a distance equal to the depth of the cup 4 and a semi-circular flange 13 formed integral with the front member extends outward horizontally therefrom serving as a 70 support for the lower edge of the cup. The said lower edge of the cup also bears against the top forward edges of the sides 10. An ear 14 taken from the metal of the flange 13 and integral with the front member 11 is turned rearwardly and provided with a threaded hole into which is screwed the lower end of the pivot screw 6.

The friction member 15 of the structure, which comprises the friction top 16, the 80 back 17 and the bottom 18 is formed of a single piece of sheet metal, the top being substantially circular and of approximately the same size as the top of the cup 4. The back and bottom portions are of the right 85 width to fit between the sides 10 and the ears 19 provided at each side of the top near the rear fit into notches 20 cut into the top edges of the sides 10. The top 16 is provided with a central opening 21 through 90 which the screw 6 passes.

When the device is assembled the inverted cup portion 4 lies between the top 16 and the flange 13 and the pivot screw 6 passes through the top, the cup, the tube, and is 95 threaded into the ear 14. The arm 1 which is attached to the cup may be swung in a horizontal plane about the said pivot screw as an axis. The screw may be tightened to produce sufficient frictional resistance on 100 the cup so that the arm will remain in any desired position. The ears 19 in the notches 20 accurately locate the top 16 relative to the body portion 8 and when the device is fastened against the wall the back 15 is held 105 in place by engagement with said wall and the front edge of the bottom 18 engages the front portion 11 preventing movement in an outward direction.

The electric conductor wires 2 passing 110

through the tube 1 and out its open rear end into the cup 4, extend downward through the open bottom of the cup and out of the back of the bracket through a hole 22 in the back and in most cases a corresponding hole is cut in the wall to which the bracket is attached so that the wires may also pass through it.

The body member, friction member and the cup portions of this device are all readily manufactured from sheet metal by dies which makes them extremely cheap to manufacture. The arm 1 is made from tubing and only requires a very simple operation to prepare its rear end as described and the act of brazing or welding it to the cup member 4 is a simple matter and is quickly and cheaply done.

I claim:

1. A light bracket comprising a tubular arm, an inverted cup-shaped member fastened to one end of said tubular arm, a body member having vertical flanges to engage a wall surface and a horizontal flange to engage and support the lower edge of the cup-shaped member and a friction member having ears to fit into notches in the body member and adapted to engage the top of the cup-shaped member, and a pivot screw

passing through the friction member, the cup-shaped member and screwed into the body member substantially as described.

2. A light bracket comprising an inverted cup-shaped member, a tubular arm extending inside of the cup-shaped member and fastened thereto, electric wires extending through the tubular arm and out of the bottom of the cup-shaped member, a body member made of a single piece of sheet metal having vertical flanges to engage a wall surface, spaced apart side member, and a front member, a horizontal flange integral with the front member and adapted to support the inverted cup-shaped member, an ear integral with the front member having a threaded opening, a friction member comprising integrally formed top, back and bottom members, said top member having ears to fit within notches in the sides of the body member, and a pivot screw extending respectively through the top member, the cup-shaped member, the tube, and screwed into the threaded opening of said ear on the front member, all substantially as and for the purpose described.

In testimony whereof I affix my signature.

CHARLES E. BROMAN.
